US0D1087827S

(12) **United States Design Patent** (10) **Patent No.:** **US D1,087,827 S**
(45) **Date of Patent:** **** Aug. 12, 2025**

(54) **ENVIRONMENTALLY CONTROLLED
CONTAINER FOR GROWING MUSHROOMS**

(71) Applicant: **Evan Gage**, Boynton Beach, FL (US)

(72) Inventor: **Evan Gage**, Boynton Beach, FL (US)

(**) Term: **15 Years**

(21) Appl. No.: **29/888,109**

(22) Filed: **Mar. 28, 2023**

(51) **LOC (15) Cl.** **11-02**

(52) **U.S. Cl.**

(57) **CLAIM**

The ornamental design for an environmentally controlled container for growing mushrooms, as shown and described.

DESCRIPTION

FIG. 1 is a front perspective view of an environmentally controlled container for growing mushrooms, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.
